SOLUTION SPRAY GUN

James T. Clark, 118 W. Railroad Ave.,
Fort Morgan, Colo. 80701

Filed Feb. 27, 1967, Ser. No. 5,956

Term of patent 14 years

(Cl. D62—2)

FIG. 1 is a top plan view of a solution spray gun showing my new design;

FIG. 2 is a side elevational view thereof, the opposite side is a mirror image of the side shown;

FIG. 3 is a front elevational view thereof; and

FIG. 4 is a horizontal cross-section taken looking downwardly on the line 4—4, FIG. 2.

I claim:

The ornamental design for a solution spray gun, as shown and described.
